UNITED STATES PATENT OFFICE.

PETER FRANKLIN PANABAKER, OF WAYNE, NEBRASKA, ASSIGNOR OF TWO-FIFTHS TO JESSE SAMUEL HAKE, OF SAME PLACE.

CHECK-ROW ATTACHMENT FOR CORN-PLANTERS.

SPECIFICATION forming part of Letters Patent No. 362,309, dated May 3, 1887.

Application filed January 24, 1887. Serial No. 225,330. (No model.)

To all whom it may concern:

Be it known that I, PETER FRANKLIN PANABAKER, a citizen of the United States, and a resident of Wayne, in the county of Wayne 5 and State of Nebraska, have invented certain new and useful Improvements in Check-Row Attachments for Corn-Planters; and I do hereby declare that the following is a full, clear, and exact description of the invention, which 10 will enable others skilled in the art to which it appertains to make and use the same, reference being had to the accompanying drawings, which form a part of this specification, and in which—

15 Figure 1 is a side view of my improved check-row corn-planter. Fig. 2 is a top plan view of the same. Fig. 3 is a rear view. Fig. 4 is a vertical sectional view on line xx , Fig. 2. Fig. 5 is a similar view taken on the same 20 line, but looking in the opposite direction. Fig. 6 is a perspective detail view of the supporting-bearing for one end of the operating-shaft. Fig. 7 is a similar view of the casting secured to the middle of the forward shaft or 25 bar. Fig. 8 is a similar view of one of the uprights having the shaft-supporting catches. Fig. 9 is a front view of the machine, and Figs. 10, 11, 12, and 13 are detail views.

Similar letters of reference indicate corresponding parts in all the figures.

30 My invention has relation to that class of check-row corn-planters in which the operating-shaft is provided with radiating spokes or legs at its ends, which legs or spokes travel upon the ground with their ends, revolving 35 the shaft, and at the same time marking the hills planted; and it consists in the improved construction and combination of parts of such a planter, as hereinafter more fully described 40 and claimed.

In the accompanying drawings, the letters A A indicate two upright brackets secured upon the cross-piece A', connecting the forward ends of the runners B' B', the rear ends of 45 which support the seed-tubes C' C', upon the upper ends of which the rear cross-piece, D', is secured, having the seed-boxes E' E' secured upon its ends and having the dropping-slide F' upon it, the arms G'' G'', which connect the 50 planter to the sulky-frame, being attached with their forward ends to the said rear cross-

piece. A transverse shaft or rod, B, is secured in the upper ends of the upright brackets by means of caps or bearings a a, and three arms, C, C, and D, connect the rod to the operating-shaft E. 55

The forward ends of the two outer arms, C C, are provided with bearings b, and oblique braces F F are secured to the arms and have their forward perforated ends fitting upon the rod or shaft, the said ends being spaced apart from the bearings by means of sleeves c, fitting upon the rod or shaft. The rear ends of the arms are provided with horizontally-flattened sockets e, into which pins or bolts z upon the shanks of transverse bearings d for the operating-shaft may slide and turn, the said sockets and bearings forming swivel-joints for the operating-shaft. 60

The forward end of the central arm, D, is 70 provided with a vertically-slotted bearing or casting, f, which may turn and slide upon the forward shaft or rod, and the rear end of the arm is provided with a casting, g, formed with a bearing for the shaft and with a forwardly-projecting box for holding the end of the arm, the sides of the said box, which is open at the ends and at the top, being provided with pivotal pins y y. L-shaped arms or levers G G are 75 pivoted with their upper arms upon these pivotal pins or lugs, and are formed with flat arms at right angles to the upper arms and with segmental slots G' in their upper ends.

Arms J are secured with their sleeved centers upon the operating-shaft and have their ends 80 preferably provided with anti-friction rollers J', and the arms are secured by means of set-screws v' at both sides of the box g, and have their ends projecting at equal angles to each other, two arms being shown in the drawings 85 projecting at each sleeve and at right angles to each other.

The forward end of the central connecting-arm, D, has a T-shaped lever, H, pivoted upon it, and the rear end of this lever is formed with a cross-head, to the ends of which the ends of two rods, K K, are pivoted, having their rear bent ends sliding in the segmental slots G' in the upper ends of the L-shaped arms G. 95

A casting, M, is secured with two bearings 100 at its upper end, having set-screws s s to the middle of the forward shaft or rod, and the

lower portion of the casting is formed with a socket, *v*, while the forward face of the casting is provided with a pivotal pin or lug, *t*, and the two bearings and their set-screws confine 5 the vertically-slotted casting at the forward end of the central connecting-arm.

A lever, *L*, is pivoted upon the pivotal pin or lug *t*, and has the forward end of the T-shaped lever inserted into a longitudinal slot 10 in its upper end, and the lower end of the lever is inserted into a transverse eye at the forward end of a lever, *N*, pivoted to rock in a horizontal plane upon a stud projecting from a frame-piece, *O*, secured with its forward end 15 in the socket *v* in the casting *M*, and secured with its rear end to the rear cross-piece of the planter-frame by means of angle-iron *P*. The rear end of the lever *N* is pivotally connected to the dropping-slide and operates the dropping 20 mechanism, which may be of any desired construction.

Two hubs or castings, *i i*, are secured with their central sleeves, *W*, upon the ends of the operating-shaft, the hubs or sleeves having 25 grooves for the reception of feathers *w*, securing them to the ends of the shaft. The castings are formed with two intersecting boxes formed by rectangular flanges at the corners of the casting, and the legs or spokes *I* are secured between these flanges, being preferably 30 "halved in" or cut away at their middles and secured together with the said halved-in portions crossing within the boxes, the central sleeves passing through the middles of the 35 united diametrical spokes.

Knees *j* are secured with their inner socketed ends to the ends of the spokes, and the outer ends of the knees are provided with sharp transverse knife-blades *h*, which serve 40 as markers.

Two uprights, *Q*, are secured upon the rearwardly-extending arms which connect the planter-frame with the wheeled frame, and the lower ends of these uprights are formed 45 with transverse bearings, in which a shaft, *S*, rocks, the said shaft having arms *m m* projecting from it through apertures in the bases of the uprights and having a treadle, *n*, near its middle, by means of which the shaft may be 50 rocked.

Shouldered catches or latches *k* are pivoted with their lower ends in the lower ends of the uprights and have forwardly and upwardly curved arms *o* at the said ends, which arms are 55 connected to the arms of the rocking treadle-shaft by means of small chains or links. The upper forwardly-bent ends of the latches slide in suitable slots in the upper ends of the uprights, and are provided at the forward ends 60 with cross-heads *p*, which prevent the latches from dropping rearward more than sufficient to support the operating-shaft, which may push the latches forward when raised, and afterward rest upon the shoulders of the latches 65 when the latches have fallen back again.

By depressing the treadle upon the rock-shaft when the operating-shaft is supported

upon the latches, the shaft and its arms will be tilted forward, tilting the arms of the latches forward through the links or chains, which 70 will allow the operating-shaft to drop again.

It will be seen that when the machine is drawn across a field and the operating-shaft is down, the knives or markers of the spokes or legs will engage the ground and revolve the 75 operating-shaft, which will cause the radiating arms of the said shaft to alternately tilt the L-shaped arms, which, by drawing upon the connecting-rods, will rock the T-shaped lever, and through it the vertical lever, which will 80 rock the horizontal lever, which slides or reciprocates the dropping-slide, and, as the arms upon the operating-shaft project at equal angles from the shaft, the distances between the several hills planted will be the same. 85

The operating-shaft is twice as long as the width of the planter-frame, and a portion. one-half the width of the planter-frame, projects at each side of the machine, so that when the machine is turned at the end of a row the 90 marker of the spoke at that side to which the machine is turned is placed into the last mark made by one of the markers of the same side, so that in starting the machine upon the return trip the markers of that side will strike 95 all the marks made upon the former trip, causing the hills now planted to be in exact lines with the hills planted upon the former trip, and thus causing the hills to be planted in check-row, or rows intersecting each other at 100 right angles.

The operating-shaft is raised during the turning of the machine, as well as when the machine is to be transported from one place to another, and the shaft is supported upon the 105 shoulders of the latches, keeping the markers out of contact with the ground, and the shaft may be turned when it is raised, so as to bring a marker to register and drop into the exact mark made in the last row, enabling the machine to be started correctly.

The operating-shaft being journaled in the rear ends of the arms, which are pivoted with their forward ends upon the forward transverse shaft or rod and have the two swiveled connections with the rear ends of the two side arms, the said shaft is thus enabled to rock and be raised or lowered at its ends in traveling over rough ground without interfering with its operation, and the slotted ends of the several levers will 110 allow a certain amount of play for the said levers, giving play as well for the irregular position of the operating-shaft as for the levers in operating the dropping-slide.

The operating-shaft is preferably provided 115 with four registering marking-arms at each end, although a greater number may be employed, and, if desired, the arms operating the L-shaped arms may be of a greater number than the marker legs or spokes, each sleeve having three or more arms projecting from it, and the arms of one sleeve bisecting the angles formed between the arms of the other sleeve, and if a sufficient number of arms is employed 130

the machine will drill the corn in rows instead of dropping it in checked hills.

Having thus described my invention, I claim and desire to secure by Letters Patent of the 5 United States—

1. In a check-row attachment for corn-planters, the combination of a transverse shaft secured upon the forward portion of the planter-frame, an operating - shaft having radiating 10 marking legs or spokes upon its ends and having radiating arms at its middle operating the seed-dropping mechanism, two arms pivoted at their forward ends to the forward shaft and having swiveled bearings at their rear ends 15 for the operating - shaft, and an arm at the middle having a vertically-slotted casting at its forward end for the forward shaft and a bearing at its rear end for the operating - shaft, as and for the purpose shown and set forth.
2. In a check-row attachment for corn-planters, the combination of a transverse shaft at the forward portion of the planter-frame, an operating - shaft having radiating marking-arms at its ends and having radiating arms at 20 its middle operating the seed-dropping mechanism, an arm having a vertically-slotted casting at its forward end sliding upon the forward shaft and having a bearing at its rear end for the operating-shaft, arms having bearings at the forward ends for the transverse forward shaft and having horizontally-flattened sockets at their rear ends, and transverse bearings for the operating-shaft, having forwardly-extending bolts turning and sliding in the flattened sockets of the arms, as and for the purpose shown and set forth.
3. In a check-row attachment for corn-planters, the combination of an operating - shaft having radiating marking legs or spokes at 40 its ends and having radiating arms arranged in two alternating sets upon the middle of the shaft, two L-shaped arms pivoted with the upper arms and having the radiating arms of the operating-shaft engaging the lower bent portions and formed with segmental slots in the upper ends, a T-shaped lever pivoted to rock in a horizontal plane upon the forward end of the frame, connecting-rods pivoted to the ends of the cross-head of the lever and having their 45 bent rear ends sliding in the segmental slots in the L-shaped arms, a lever pivoted upon the forward end of the planter-frame, rocking in a transverse and vertical plane, and having the forward end of the T-shaped lever inserted 50 into a flat eye at its upper end, and a lever pivoted to rock in a horizontal plane and having the lower end of the vertically - rocking lever engaging a flat eye in its forward end and operating the seed-dropping slide with its 55 rear end, as and for the purpose shown and set forth.
4. In a check-row attachment for corn-planters, the combination of an operating - shaft having radiating spokes or marking-legs at its ends and having radiating arms at its middle 60 for operating the seed-dropping mechanism, two uprights upon the planter-frame having transverse bearings in their bases formed with openings at the forward sides, latches or catches pivoted with their lower ends in the 65 uprights and having their forwardly - bent shoulder portions sliding in slots in the upper ends of the uprights and formed with cross-heads upon the said ends, arms projecting from the lower ends of the latches at their 70 pivotal points, and a rock-shaft journaled in the bearings in the bases of the uprights and formed with a treadle at its middle and with forwardly-projecting arms extending through the apertures in the bearings and having their 75 ends connected by links or chains to the ends of the arms of the latches, as and for the purpose shown and set forth.
5. The casting M for the forward transverse shaft, formed with the two transverse bearings 80 for the shaft and with a socket at its lower end and with the pivotal lug or pin t, as and for the purpose shown and set forth.
6. In a check-row attachment for corn-planters, the combination of the arm D, the operating - shaft, the casting g, having the transverse bearing for the operating-shaft, and the forwardly-projecting box open at the ends and at the upper side and having laterally-projecting pins or lugs upon the sides, and the 90 L-shaped arms G, fulcrumed upon the studs or lugs, as and for the purpose shown and set forth.
7. In a check-row attachment for corn-planters, the combination of the operating - shaft, 100 castings i, having sleeves at their centers formed with grooves and secured by means of feathers upon the ends of the operating-shaft, arms I, halved in at their middles and formed with perforations at their middles for 105 the sleeve, fitting upon each other and within boxes crossing each other in the casting and upon the sleeves with the perforations, and knees socketed upon the outer ends of the arms and having small knife-blades upon their 110 outer ends, as and for the purpose shown and set forth.

In testimony that I claim the foregoing as my own I have hereunto affixed my signature in presence of two witnesses.

PETER FRANKLIN PANABAKER.
